UNITED STATES PATENT OFFICE.

FRANCIS J. HANRAHAN, OF RUPERT, PENNSYLVANIA.

NUT AND PIPE WRENCH.

1,109,061.

Specification of Letters Patent. Patented Sept. 1, 1914.

Application filed July 31, 1913. Serial No. 782,344.

To all whom it may concern:

Be it known that I, FRANCIS J. HANRAHAN, a citizen of the United States, residing at Rupert, in the county of Columbia and State of Pennsylvania, have invented a new and useful Nut and Pipe Wrench, of which the following is a specification.

The present invention appertains to wrenches, and aims primarily to provide a novel and improved nut and pipe wrench.

It is the object of the present invention to provide a device of the character indicated which may ordinarily be employed as a nut wrench or common wrench, and which may be readily converted into a pipe wrench.

Another object of the present invention is to provide a wrench, the jaws of which are unencumbered so as to be capable of grasping nuts and other objects, pipe gripping members being applicable to the shank or stock of the wrench so as to coöperate with the respective jaws for engaging the pipe or other circular stock.

A further object of the present invention is to provide novel and improved means for quickly adjusting the movable jaw.

It is also within the scope of the present invention to provide a combination wrench of the character indicated which shall be simple, light, durable, substantial, and inexpensive in construction, as well as serviceable, convenient and efficient in its use.

With the foregoing general objects outlined and with other objects in view, which will be apparent as the description proceeds, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a side elevation of the improved wrench illustrating the pipe gripping members applied thereto. Fig. 2 is a longitudinal section. Figs. 3 and 4 are sectional views taken on the lines 3-3 and 4-4 of Fig. 1. Fig. 5 is a perspective view of one of the pipe gripping members. Fig.

6 is a perspective view of the other pipe gripping member.

In carrying out the invention, reference being had in detail to the drawing, there is provided a suitable metallic stock or shank 1 having the stationary jaw 2 at its outer end, and having its other end offset, as at 3, to provide a handle. The shank or stock 1 is provided with the dove-tailed tongue 4 extending from the stationary jaw 2 to the offset portion, the said tongue being provided with a series of transverse notches 5 extending from the inner end of the tongue to a point short of the outer end.

A slide 6 is movably carried by the stock, the slide being provided with a dove-tailed groove or channel 7 engaging the tongue 4. The slide 6 is provided with an angular extension 8 at its outer end forming the movable jaw, which is adapted to ordinarily coöperate with the stationary jaw 2 for grasping nuts and other angular objects. The faces of the jaws 2 and 8 are flat and smooth and are disposed at right angles to the stock in order that the jaws may engage various objects without difficulty.

In order to lock the slide 6 and movable jaw in any adjusted position, a latch or plate 9 is carried by the slide 6, the said latch or plate 9 resting against that face of the slide 6 remote from the stock 1 and having its outer end engaging loosely over the pin 10 carried by the slide 6 adjoining the jaw 8. The other or inner end of the latch or plate 9 is bent angularly over the inner end of the slide 6, in order to engage the respective notches 5. A thumb screw 12 is passed loosely through the latch 9 adjoining its inner end and is threaded into the slide 6 to press the angular end 11 of the latch into engagement with the notches 5, while a coiled wire compression spring is seated in a socket 14 provided in the slide 6 intermediate the screw 12 and pin 10, so as to press the latch 9 outwardly or out of engagement with the notches 5. It will thus be evident that when the screw 12 is tightened, the end 11 of the latch will be maintained in engagement with the respective notch 5, and when the screw is loosened, the spring 13 will throw the latch out of engagement with the notches 5. The pin 10 serves to prevent the latch from swinging sidewise upon the screw 12 as a pivot.

When the latch 9 is released, it will be evi-

dent that the slide may be withdrawn from the tongue 4.

The pipe gripping attachments or members embody a block 15 having the dove-tailed groove 16 at one end adapted to engage the tongue 4, and a block 17 having the dove-tailed groove 18 at one end adapted to engage the said tongue. The blocks or members 15 and 17 are interchangeable and 10 are preferably similar in contour to the respective jaws 2 and 8, and have their remote faces flat so as to rest snugly against the faces of the jaws, the other or adjacent faces of the blocks 15 and 17 being preferably inclined, so as to diverge away from the stock 15. The outer or exposed face of the block 15 is preferably toothed so as to bite the pipe or other stock, while the outer or exposed face of the block 17 is smooth and provided 20 with the longitudinal dove-tailed groove 19 extending from the stock, a supplemental block or pipe engaging member 20 being movable along the face of the block 17, and the supplemental block 20 having a dove-tailed tongue 21 working within the groove 19 of the block 17. The face of the supplemental block 20 is preferably toothed so as to bite the pipe or other stock.

In use, when the members 15 and 17 are 30 detached from the stock, the jaws 2 and 8 are adapted to coöperate for grasping nuts or other articles, it being observed that the movable jaw 8 may be readily adjusted by loosening the thumb screw 12, and may be 35 secured in position by tightening the said screw. The offset handle 3 permits the hand of the operator to grasp the same, without being engaged by the slide 6 when the same is moved downwardly or inwardly.

40 When it is desired to convert the device into a pipe wrench, the slide 6 is removed, by withdrawing it from the inner end of the tongue 4, the thumb screw 12 having been loosened, which will permit the members 15 and 17 to be applied to the stock. In applying the members 15 and 17 to the stock, the dove-tailed grooves 16 and 18 of the respective members 15 and 17 are engaged over the inner end of the tongue 4, and the 45 slide 6 is then applied to the said tongue. The member 15 is slid against the stationary jaw 2 while the movable jaw 8 is slid against the member 17, the member 17 being slid to the required position by the adjustment of 50 the slide. The toothed pipe gripping member 20 is adapted to slide longitudinally of the member 17, the pipe being adapted to be grasped between the toothed faces of the members 15 and 20 in order that when the 55 handle is swung, the member 20 in engaging or biting the pipe, will be slid inwardly, so that the pipe may be more tightly gripped, as will be apparent. In this manner, the de-

vice may serve especially as a pipe wrench, it being observed that the members 15 and 17 are readily attachable to and removable from the stock.

It is to be observed that the jaws 2 and 8 are not encumbered, in order that they may readily grasp nuts and other objects, and it is also to be observed that the pipe gripping attachments are simple, they being readily carried in the vest pocket or the like. The other advantages and capabilities of the present device will be apparent from the foregoing taken in connection with the drawing.

What is claimed as new is:—

1. In a wrench, a stock having a jaw at one end, a removable jaw slidably engaging the stock, the faces of the jaws being flat, means for locking the movable jaw to the stock, a pair of removable interchangeable supplemental members slidably engaging the stock and having their remote faces flat and resting snugly against the faces of the jaws, the adjoining faces of the supplemental members diverging away from the stock, the last mentioned face of one supplemental member being toothed, and a toothed element slidably carried by the last mentioned face of the other supplemental member and movable to and from the stock.

2. In a wrench, a stock having a jaw at one end and a dove-tailed portion extending from the said jaw, a removable jaw having a dove-tailed portion slidably engaging the said dove-tailed portion, the faces of the two jaws being flat and disposed at right angles to the stock, means for locking the movable jaw to the stock, a pair of removable interchangeable supplemental members having dove-tailed portions slidably engaging the first mentioned dove-tailed portion, the remote faces of the supplemental members being flat and resting snugly against the faces of the jaws, the adjoining faces of the supplemental members diverging away from the stock, the last mentioned face of one supplemental member being toothed, and the last mentioned face of the other supplemental member having a dove-tailed portion extending from the stock, and a toothed element slidable upon the last mentioned face of the last mentioned supplemental member and having a dove-tailed portion slidably engaging the dove-tailed portion thereof.

In testimony that I claim the foregoing as my own, I have hereto affixed my signature in the presence of two witnesses.

FRANCIS J. HANRAHAN.
